UNITED STATES PATENT OFFICE.

HANS HARTMAN AND JULIUS ERDOES, OF NEW YORK, N. Y.

AUTOGRAPHIC TIME-RECORDER.

1,306,481.

Specification of Letters Patent. Patented June 10, 1919.

Application filed April 28, 1917. Serial No. 165,073.

To all whom it may concern:

Be it known that we, HANS HARTMAN, a subject of Austria-Hungary, and JULIUS ERDOES, a citizen of the United States, residing at New York, in the county of New York and State of New York, have invented certain new and useful Improvements in Autographic Time-Recorders, of which the following is a specification.

This invention relates to a time recorder and particularly to an autographic time recorder.

We aim to provide a novel, improved and simplified construction especially capable of manufacture at low cost in compact form and of small size. However, we particularly aim to provide a construction in which fraudulent manipulation or tampering is impractical, one having means to hold and permit access to the record tape through operation of a closure and one in which the record tape may be removed. Additional important objects will be pointed out as the description progresses.

One preferred embodiment is illustrated in accompanying drawings, wherein:

Figure 1 is a front elevation; Fig. 2, a view similar to Fig. 1 but with the cover removed and parts broken away to disclose details; Fig. 3 is a cross section on line A—A of Fig. 2; Fig. 4 is a cross-section on line B—B of Fig. 2; Fig. 5, is a cross section on line C—C of Fig. 2; Fig. 6 is an enlarged view of the parts at the recording point but with the closure open and Fig. 7 is a detail section, showing the fastening means of a shaft bearing employed.

Referring specifically to the drawings, we provide a suitable casing which may comprise a container, 1 having a cover 2 hinged thereto at 34 and 35, and adapted to be secured in closed relation thereto by a suitable lock 36 provided with a lug 36^a to overlap a keeper lug 36^b (see Fig. 4).

A frame 5 is secured within container 1 and supports a platen 12 below an opening 19 which permits access to a paper or record tape 17 which may rest upon the platen to receive an inscription or signature and a time registration. The platen preferably has its upper edges rounded.

At 3 a suitable clock is disposed within container 1, being preferably mounted on a rubber mat 41 which will reduce noise occurring by engagement of the clock with the container. The usual turnable hand spin-

dle of the clock is shown at 26 and a disk 25 is rigidly secured to the spindle, in place of the usual hands. Arms 27, 28, 29 and 30 radiate from disk 25 and at their outer ends 60 are secured to a dial in the form of a ring 4. This dial ring is capable of slight vertical tilting as members 27, 28, 29 and 30 are springs and resiliently support it. A tape of paper or other material passes intermediate the dial and platen and is normally freely movable there between. Directly beneath the tape which is designated 17, the platen is recessed and filled with a rubber block or plate 42 which will render printing operations noiseless, furnish a yielding stamping surface and prevent injury to the type or printing surface. The clock dial 4 turns beneath a sight opening 33 in cover 2 (Fig. 1), so that the time may be readily 75 observed. The time graduations on the face of the dial coöperate with a pointing or indicating means 33^a (Figs. 1 and 2) also arranged opposite opening 33.

The inner face of the dial 4 has imprinting 80 projections as in Fig. 6 to engage a printing inked ribbon 18 normally traveling freely between the projections and the tape or record 17. A presser head 37 is moved into contact with the dial to effect a registration and this 85 head is preferably maintained above the dial by a leaf spring 39 suitably fastened at 40 to cover 2.

The printing projections are arranged say 45° in advance of the indications of the upper face of the dial 4; the indications of the upper face are recessed to make a smooth surface, that is to say the same time as indicated at opening 33 will be printed on the strip 17 over the rubber platen 42. 90

A closure 20 for the opening 19 is hinged or pivoted by a pin 22 to ears 23 integral with cover 2. 95

A cam 24 forms part of closure 20 and is adapted to press head 37 against dial 4. A 100 pin or point 38 is provided on head 37 to pierce the paper roll and a recess to receive said point is provided in the rubber block 42 as shown in Fig. 5. The paper strip 17 may be observed through an opening in closure 105 20 covered by a transparent panel 21. Closure 21 is manipulated by a knob 20^a and is fastened by a vertically slideable latch bar 48, engaging a hook 48^a on the closure. A lug 47 projects laterally from the bar 48 and 110 a spring leaf connected to cover 2 bears against hook 48^a and urges the hook and

closure outwardly and prevents re-locking until the hook is pushed past the latch, latch 48 is secured slidably to cover 2 by set screws 48^b extending through an elongated 5 slot of the latch. At 48^c the latch has a beveled end to enable the hook 48^b to better pass the latch on closing the closure 20.

By reference to Figs. 3 and 4 it will be noticed that rollers 6 and 7 are provided. 10 The paper strip is fastened to roller 6 and passes across the platen 12 and then if fastened to roller 7, the paper is unwound from roller 6 onto 7. The printing inked ribbon is wound around a roller or drum 10 over 15 roller 8, the paper at the platen roller 9 onto roller 11. The shaft of roller 10 is designated 10^c and is rigidly secured to the sides of frame 5. However, a coil spring 10^b tends to wind the inked ribbon on the 20 drum. The shafts for rollers 7, 8, and 9 may be secured in any suitable manner to frame 5. Also the rollers 6 and 11 may be suitably supported from the frame, but they are preferably removable so as to remove and replace 25 the paper tape or strip and the inked ribbon. The shaft of roller 11 is designated 53 and that of roller 6 is designated 6^c. These shafts respectively rest removably in notches 6^a of one side of the frame 5 and are se- 30 cured therein by locking bearings 43 and 44 respectively pivoted at 43^a and 44^a to said side.

These bearings are slightly resilient so that lugs 43^a may clip into corresponding 35 recesses in the side and prevent movement of these bearings. The other ends of the shafts may be sliding sections 6^a, inwardly yieldable against and urged outwardly by springs 6^b (see Fig. 5). The section 6^a enters 40 notches in the adjacent wall of frame 5. Rollers 6, 7, 8, 9, 10 and 11 respectively have end flanges 6^a, 7^a, 8^a, 9^a, 10^a and 11^a to prevent displacement of the ribbon and paper strip there from. Any means may be em- 45 ployed to fasten the ends of the paper and ribbon to the rollers.

On shaft 7 an escapement or tappet wheel 45 is keyed and its teeth receive lug 47 between them and move said lug to slide latch 50 48 and release hook 48^b and the closure 20. Also a gear wheel 51 is keyed to shaft 7 and it meshes with a gear wheel 52 keyed to shaft 53. Shaft 7 has an extension 7^c which terminates in a square portion 50 which may 55 be engaged by a winding key insertible through an opening 50^a in casing section 1.

The winding spindle of the clock 3 has a square head at 31 of the same size as head 50 so that the same key which winds the 60 shaft 7 may wind the spindle 31. Said key is insertible through an opening 32 in the cover to engage head 31.

The apparatus may be vertically disposed as in the drawings. With the paper strip in 65 place, the inked or printing ribbon in place,

the clock wound drum or roller 10 wound and closure 20 locked by latch 48, the machine is ready for operation. To register a key must be inserted through opening 50^a and engaged with head 50. The key is 70 turned to the right, accordingly turning shaft 7 and the escapement wheel 45, causing a tooth of the latter to strike lug 47 and raise latch 48, thus releasing closure 20 and enabling spring 49^a to urge the hook 48^b and 75 closure 20 outwardly.

At the same time, shaft 7 through the gear wheels 51 and 51 imparts movement to shaft 53 and as a result all of the rollers and the printing ribbon of the rollers and the print- 80 ing ribbon and paper tape are moved against the tension of spring 10^b. Upon closure 20 raising or being raised, the cam 24 presses head 37, against the tension of its spring 39 into contact with the dial 4 which yields so 85 that its printing characters engage the printing ribbon and impress or print the time in ink on the paper tape. At the same time, the registrant may write his name or other appropriate data on the paper or record, 90 through the opening 19. During the print- 95 ing operation lug 38 penetrates the paper and holds it or prevents return movement urged by spring 10^b.

Return movement is also impossible be- 95 cause the tappet wheel 45 will strike with its nearest tooth backward against lug 47 respectively of slide latch 48 and as the same cannot give way downward, only a very limited return motion of the shaft 7 will re- 100 sult. This is important because tension of the same would tear the paper. The paper therefore cannot move backward, if it is at- 105 tempted to move for the purpose of making a fraudulent registration. After the regis- 110 tration is completed the paper cannot move forward until the closure 20 is locked. The lug 47 always remains between two of the teeth of the escapement wheel so that spring 10^b cannot move the tape or ribbon back- 115 ward. The key cannot operate to move the tape or ribbon backward, as the teeth of the escapement wheel abut the latch 49 which abuts hook 48^b. To make the next regis- 120 tration, the key is inserted through opening 50^a and shaft 7 is turned as before. The registrations are successively made in the manner indicated. The record tape may be removed at stated intervals or whenever de- 125 sired by cutting off a part or exchanging it entirely and the inked ribbon also can be readily exchanged by shifting bearings 44 and 43.

Changes in the details may be resorted to as I have merely illustrated and described an embodiment.

We claim:

1. A recording machine having a record- 130 ing medium, inking means and printing means associated therewith, and a driving,

connection between said means so that one means will move through operation of the other means, means operable to rewind the recording medium, and means to penetrate

5 the medium during a printing operation to hold the medium against the action of the rewinding means.

2. A recording machine having a printing mechanism and a recording mechanism, a 10 movable member normally preventing access to the medium, a fastening device for the member, said device engaging an escapement means, and means associated with the member to arrest movement of the recording medium.

3. A recording machine having a recording medium, rollers for said medium, a platen over which said medium travels, an inking ribbon to travel over said medium,

20 rollers for said ribbon, a gear wheel associated with one of the rollers of the recording medium, a gear wheel in mesh with said gear wheel associated with one of the rollers of the inking ribbon, a rewinding spring

25 associated with one of the rollers, a pivoted member controlling access to the recording medium, a fastening member for said member, an escapement wheel associated with one of said rollers and with said fastening

30 member, a cam on the first mentioned member, a presser in operative relation with the cam, a clock having a turnable dial, and said dial movable beneath said presser.

4. In a recording apparatus of the character described, a clock mechanism in direct association with the time printing means, a recording medium, means to move said recording medium, an opening to permit access to said recording medium, said opening being

40 normally closed by means which will, when opened, force the printing means into con-

tact with said recording medium and penetrate said medium during a printing operation to hold the recording medium against the moving means.

5. In a time recording apparatus of the character described, a clock mechanism in direct association with time printing means, a recording medium, rollers for said medium, supporting means over which said medium travels, an opening to permit access to said recording medium arranged opposite said supporting means, eccentrically pivoted means to keep said opening normally closed and arranged to force the printing means into contact with the recording medium when opened and means to penetrate the recording medium during a printing operation to hold the recording medium against motion of said medium.

6. In a time recording apparatus, a clock having a turnable printing dial, a recording medium, means to move said medium, means to support said medium, over which said medium travels, an opening to permit access to said recording medium, said opening arranged opposite said supporting means, eccentrically pivoted means to keep said opening normally closed and to force the printing dial into contact with the recording medium when opened and to penetrate said medium during a printing operation to hold the same against the moving means.

In testimony whereof we affix our signatures in the presence of two witnesses.

HANS HARTMAN.
JULIUS ERDOES.
